UMBRELLA FERRULE

Joseph Levin, Lancaster, Pa., assignor to Polan, Katz & Company, Baltimore, Md.

Application April 30, 1943, Serial No. 485,218

5 Claims. (Cl. 135—34)

This invention relates to an improved one-piece ferrule for umbrellas.

An object of this invention is to provide a ferrule which is formed of one piece having an annular groove in the lower portion thereof within which the center of the cover is adapted to be engaged, the ferrule being removable with the cover so that the cover assembly may be constructed as a removable or replaceable unit.

Another object of this invention is to provide in combination an umbrella cover having rib tips on the outer margin thereof and a ferrule secured to the center of the cover, the ferrule being a one-piece element formed with an annular groove at its inner end and the cover being so arranged at its center as to be firmly retained within the groove.

A further object of this invention is to provide an improved ferrule which can be made out of any suitable material and may be molded or otherwise shaped to provide the desired construction, the center of the cover being stitched and drawn tightly into the groove.

The invention consists of the novel construction, combination and arrangement of parts as will be more specifically referred to and illustrated in the accompanying drawing wherein is shown an embodiment of this invention, but it is to be understood that changes, modifications and variations may be resorted to which fall within the scope of the invention as claimed.

In the drawing:

Figure 1 is a fragmentary sectional view of an umbrella and cover embodying an improved ferrule constructed according to an embodiment of this invention.

Figure 2 is a fragmentary sectional view taken on the line 2—2 of Figure 1.

Figure 3 is a detail side elevation of the ferrule, and

Figure 4 is a fragmentary sectional view of the cover removed from the ferrule, showing the manner of applying the stitches to the center of the cover.

Referring to the drawing, the numeral 10 designates generally an umbrella stick having adjacent the outer end thereof a circumferentially split ring 11 with which ribs 12 are pivotally secured by means of a wire 13. A cover 14 of flexible material is adapted to engage over the ribs 12 and is provided at the outer marginal portions thereof with tips 15 which are secured to the cover 14 by stitching 16. The outer ends of the ribs 12 are reduced as at 17 and removably engage in sockets 18 provided in the tips 15.

A ferrule generally designated as 19 is adapted to be removably mounted on the outer end of the stick 10. The ferrule 19 includes a body 20 formed with an inwardly opening socket 21 within which the outer end of the stick 10 is adapted to be firmly engaged. The socket 20 also includes an opening 22 of slightly larger diameter than the diameter of the socket 20 for receiving the outer projecting portion 23 of the ring 11. The ferrule body 20 at its inner portion is formed with an annular groove or channel 24 within which the center of the cover 14 is adapted to be snugly and tightly mounted. The groove 24 forms an inner flange 25 which is integral with the ferrule body 20 and which is adapted to contact with the outer side of the ring 11.

The cover 14 has an inner reinforcing disc-shaped member 26 interposed between the inner side of the cover 14 and the outer side of the flange 25. As shown in Figure 2, the cover 14 and the reinforcing member 26 are provided with central registering openings 27 and the central portions of the cover 14 and reinforcing member 26 are firmly secured together by overcasting stitching 28. A puff 29 is also secured to the cover 14 being secured to the outer side of the cover 14 by stitching 30.

In the mounting of the cover 14 on the ferrule 19, the cover 14 with the reinforcing member 26 is forced over the periphery or outer side of the ferrule 19 and then loosely positioned within the groove 24. The stitching 28 is then extended through the cover 14 and the reinforcing member 26, the stitching being drawn tight so as to constrict the central portion of the cover 14 within the groove 24. After the stitching 28 has been applied to the cover 14 and the reinforcing member 26, the puff 29 may be slipped over the ferrule 19 and then forced into the groove 24.

The stitching 30 securing the puff 29 to the cover 14 is in the form of relatively long stitches which preferably engage only through the cover 14 and the two sides of the puff 29. The stitching 30 is positioned outwardly a slight distance from the stitching 28. The stitching 28 is applied by inserting a needle through the cover 14 and the reinforcing member 26 within the groove 24, the needle being inserted on substantially a tangent to the ferrule. The cover 14 by means of the stitching 28 is thus firmly and snugly held within the groove 24 so that the ferrule 19 forms a removable part secured to the cover 14 and may be removed from the frame with

the tips 15. In this manner a new cover may be readily applied to the umbrella frame by merely inserting the ferrule over the outer end of the stick and securing the tips 15 to the outer ends of the ribs with the cover finally tied to the ribs between the ends thereof.

A ferrule constructed according to this invention will eliminate a number of steps necessary in assembling the umbrella cover and also eliminate an appreciable amount of material necessary to form the ferrule.

What I claim is:

1. In an umbrella having a frame including a stick and ribs, a cover and tips secured to the outer margin of the cover; a ferrule secured to the center of the cover and telescoping the outer end of the stick, said ferrule comprising a tapered body formed with an inwardly opening socket and an annular groove adjacent the inner large end of said body, said cover having a central opening engageable within said groove, and stitching snugly binding said cover within said groove.

2. In an umbrella having a frame and a cover removably secured to the frame, and said frame including a stick, a ring secured to the outer portion of said stick, and a plurality of ribs pivotally carried by said ring, with said cover comprising a flexible body, a plurality of rib tips secured to the outer margin of said body, and said cover having a central opening; a ferrule fixed to said cover within said opening and removably engaging the outer end of said stick and a portion of said ring, said ferrule comprising a tapered body formed with an inwardly opening socket for receiving said stick, said socket having the inner

portion thereof of larger diameter to telescope a portion of said ring, said tapered body being formed with an annular channel adjacent the inner end thereof within which the edges of the central opening of said cover are adapted to be retained in abutting relation to the inner wall of said channel, and stitching snugly securing said channel within said groove.

3. An umbrella ferrule comprising a member formed with a stick receiving socket and having an annular channel on its outer side adjacent its inner end, said channel having an inner wall and a pair of side walls for snugly receiving the edges of the central opening of an umbrella cover with said edges in abutting relation to said inner wall.

4. In an umbrella having a cover provided with a central opening for the reception of a ferrule, a tapered ferrule having a central stick receiving opening and having a channel on its outer side, the edges of said central opening of the cover being received within said channel snugly retained therein by stitching around the said edges.

5. The method of securing an umbrella cover having a central opening to a one-piece ferrule provided with an annular groove which includes inserting the ferrule through the opening to position the edges of said opening within the groove, crowding the edges of the said central opening of the cover in abutting relation to the inner wall of the groove and constricting and binding that portion of the cover within the groove by means of overcast stitching.
